UNITED STATES PATENT OFFICE.

JAMES McCOSH EDWARDS, OF WATERLOO, IOWA, ASSIGNOR TO IOWA DAIRY SEPARATOR COMPANY, OF WATERLOO, IOWA.

OILING INDICATOR.

Application filed March 8, 1926, Serial No. 93,197. Renewed April 30, 1928.

My invention relates to improvements in oiling indicators, and the object of my improvement is to furnish convenient means for visibly indicating the oil level in mechanism lubricating sources, particularly in those which include a splash-feeding system, and which means insures constant visibility of the relative static and dynamic conditions of the lubricant while the machine is operating.

This object has been accomplished by the means which are hereinafter described and claimed, and which are illustrated in the accompanying drawings, it being understood that changes in the precise embodiment of invention herein disclosed can be made within the scope of what is claimed without departing from the spirit of the invention.

In the annexed drawings, Fig. 1 is a side elevation of the housing frame and part of the mechanism only, with parts broken away, of a centrifugal liquid separator containing my improved oiling indicating means. Figs. 2, 3 and 4 are drawings on a larger scale, Fig. 2 being a vertical medial longitudinal section from front to rear of that part of the frame which contains the oiling indicator, and Fig. 3 is a front elevation thereof with parts in cross section. Fig. 4 is a perspective view of the apertured screw-plug of said indicator.

While my invention may be applied to various kinds of mechanism employing an oil reservoir and splash-feeding means, it is especially adapted for use with a centrifugal liquid separator, whose oil reservoir and splash-feeding means is ordinarily concealed from sight. It is peculiarly necessary for the operator to be able to easily and frequently inspect the condition of the oiling, in order to replenish the supply, in case of any wastage. The moving parts of a centrifugal liquid separator are geared to produce a high speed of rotation in the driven separator bowl, wherefore it is essential that all bearings be constantly freely flushed with oil.

The housing frame 1 of a centrifugal liquid separator has at the bottom a part shaped with a considerable depression to serve as an oil reservoir 2 positioned below and to receive the drippings from the moving mechanism above. Immediately above this reservoir and with its lower part submerged in the lubricating oil therein, a relatively large gear-wheel 4 is mounted on a horizontal shaft

3 rotatable in bearing apertures in said frame, 55 said wheel meshing with threads on the spindle not shown of a separator bowl.

The front of the frame 1 has a relatively large opening 6 covered by a removably attached closure body 7 whose middle part is 60 convex outwardly with a concave hollow within to receive a part of the wheel 4 thereinto through the opening 6.

Referring to said Fig. 2, the closure 7 has an outwardly projecting boss 8 having a 65 small cupped hollow 9—10 opening into the concavity thereof and the interior of the frame 1 slightly below the axis of the gear-wheel 4. The outer part of the boss 8 is enlarged at 12 and provided with a vertical bore 13 communicating with the cavity 9 by a short sloping passage 11. Both the upper and the lower ends of the bore 13 are interiorly threaded, the upper to receive a screw-plug 14, and the lower to receive a clamping-ring 19. The screw-plug 14 has an annularly grooved depending neck 17 which terminates in a conical nipple 18, said nipple and the plug being centrally bored at 15, and the plug being transversely bored at 16, the bore 16 70 terminating in opposite parts of the groove 17, one end of the bore 16 with said groove being in communication normally with the outer end of the inclined passage 9.

Spaced vertically below said boss 8—12 is 85 another projection 20 having in its upper surface a cupped recess or socket 22 with a central conical depression 23 in communication with the outer end of a horizontal passage 21 which extends lengthwise of the boss 20 but positioned obliquely to one side of its median line to open into the interior of the frame 1 just above the normal level of oil in the oil reservoir 2 and to deliver thereinto.

The cup 22 is below and vertically aligned 90 with the bore 13 of the upper boss part 12, of the same diameter, and a short piece 24 of transparent tubular material, such as clear glass, is seated in the cup 22 and in the clamping-ring 19 above.

In operation the gear-wheel 4 is in rapid rotation and having its lowermost gear teeth submerged in oil at the normal level in said reservoir 2, its centrifugal force causes its teeth to throw upwardly a spray or mist of 105 the oil particles, of which a considerable portion subside into and are received into the wall cavity 9 of said closure 7. The cup 10

retains a portion of the oil to overflow in a steady small stream through the screw-plug passages 16 and 15 by way of the inclined passage 11, while any oil received by the annular groove 17 passes around the plug to drain into the opposite end of the diametrical passage 16.

As indicated in said Fig. 1, the oil is delivered from the nipple 18 vertically downward into the center of the cup 22-23, the stream being coherent and cylindrical while the oil level in the reservoir 2 is normal. From the cup 22-23 the oil drains through the passage 21 back into the reservoir, thus maintaining a constant circulation, while the mechanism is in operation.

This coherent stream, indicated in Fig. 1 by the numeral 25, is always visible to indicate the condition of the static oil level 20 in the reservoir whether normal or in a wasted and lowered condition due to unavoidable wastage of operation of the machine. The dynamic condition of the oil as lifted and sprayed upwardly by the wheel 4 25 is also indicated, to show that sufficient oil is splashed upon the upper bearings within said frame 1, for when the stream 25 is full and normal, the other said conditions are right. A scanty, dropping or lacking oil 30 delivery at 25 denotes that the oil level in the reservoir 2 is insufficient and should be renewed. The glass tube 24 surrounds the stream 25 in spaced relation and without contact therewith, so that it is not dimmed 35 or rendered opaque by oil deposits as is the case with some devices employing glass windows upon which the oil is splashed to denote its condition, and the tube 24 prevents entry of dust.

40 My device by its said construction eliminates the leakage which usually occurs in some other devices where glass windows are fitted in wall openings of the housing. In a centrifugal liquid separator the great speed 45 of rotation of the wheel which picks up and splashes the liquid in the reservoir throws the same with such force that it inevitably seeps through such window joints and is wasted rapidly, while befoiling both the inside of the window and the outside thereof 50 and the housing, whereby the window soon becomes so opaque as to be useless for visibility of the oiling conditions within.

55 The solid metal of the closure 7 breaks the force of the projected liquid, which therefore passes the wall cavity and conduit passages therefrom slowly and quietly, without emerging in mist or spray, but being delivered in a vertical solid coherent stream 60 into the drainage conduit which conducts the liquid back to the reservoir. As the coherent stream between the delivery conduit and the drainage conduit is slow and non-splashing, the glass tubular inclosure is not splashed by 65 it, bedimmed or rendered opaque, and no

liquid can escape to be wasted because of the tight clamping seating of this tube. This coherent stream in passing through the tube of glass surrounding it is thus always visible therethrough from a distance, and any scantiness of delivery or cessation thereof warns of the necessity for replenishing the reservoir, which has lowered so that the propelling wheel does not dip into it far enough or not at all.

Having described my invention, what I claim as new, and desire to secure by Letters Patent, is:

1. In combination, a housing having a wall cavity and an open top liquid reservoir, a 80 rotatable wheel in said housing adapted to engage liquid in said reservoir and discharge it into said wall cavity, a valve-controlled conduit for delivering liquid from said cavity outwardly and downwardly in a coherent 85 vertical stream, and a conduit having an outer open end to receive said coherent stream and drain it into said reservoir, said coherent stream being visible between said conduits from the outside of said housing.

2. In combination, a housing having a wall cavity with a cupped bottom and an open top liquid reservoir, a rotatable wheel in said housing adapted to engage liquid in said reservoir and discharge it into said wall cavity, 95 a conduit for delivering liquid from the cupped bottom of said cavity outwardly and downwardly in a coherent stream, a conduit having an outer open end to receive said coherent stream without splashing and drain 100 it into said reservoir, and a transparent vertical tubular inclosure surrounding and spaced from said coherent stream and in closed connection with the opposed ports of 105 said conduits.

3. In combination, a housing having a wall cavity and an open top liquid reservoir, a rotatable body in said housing adapted to engage liquid in said reservoir and discharge it into said wall cavity, said housing having 110 a conduit passage and a vertical open ended bore communicating therewith and by way of the conduit with the wall cavity, a rotatable vertically adjustable plug fitting said bore and having a passage therein for variable communication with said conduit passage and opening downwardly to deliver downwardly a coherent stream of liquid, and a conduit having an open outer end adapted 115 to receive said coherent stream without splashing and drain it into said reservoir.

4. In combination, a housing having a conduit in its wall and having in its lower part a liquid reservoir, a movable element in said housing adapted to engage the liquid in the 125 reservoir and splash it into said conduit above, means for adjustably controlling the passage of liquid through said conduit, said conduit being positioned terminally to deliver liquid downwardly in a coherent un- 130

splashing stream, a conduit having an open receiving end below and spaced from the termination of said delivery conduit above to receive said coherent stream of liquid therefrom and drain it back into said reservoir, and a transparent removable inclosure for the visible portion of said coherent

stream seated between said opposed conduits and spaced from the included stream to render the stream visible from the outside of 10 the housing and through the inclosure wall.

In testimony whereof I affix my signature.

JAMES McCOSH EDWARDS.
